(57) **CLAIM**

The ornamental design for an espresso tamper, as shown and described.

DESCRIPTION

The Espresso Tamper provides a tool for tamping coffee grounds for use in making espresso coffee.

FIG. 1 is a perspective view of an espresso tamper showing my new design;

FIG. 2 is a top plan view thereof; the bottom view being a mirror image and symmetrical to the top plan view; and,
FIG. 3 is a right side view thereof; the left side view thereof being a mirror image and symmetrical to the right side view thereof.
